FURNACE CONSTRUCTION

Charles V. Carroll, Minneapolis, Minn., assignor
to Wm. Bros Boiler & Manufacturing Co., Min-
neapolis, Minn., a corporation of Minnesota

Application August 7, 1944, Serial No. 548,400

15 Claims. (Cl. 110—39)

This invention relates to furnace and boiler grate constructions and particularly to furnaces and boiler constructions wherein there is utilized a shaker grate mechanism and positive feed of combustion air under the grate lip pressure, induced draft or natural draft. In furnaces and boilers of such construction and design there occurs the problem of maintaining control of the under grate air against leakage loss or air inflow (depending upon whether a positive or negative pressure exists under the grate) and also the problem of providing a hand or power mechanism for communicating power to the grates for grate shaking operations. Mechanisms heretofore provided for these purposes have not been entirely satisfactory due to air leakage, difficulty of maintenance, and inadequate power transmission to the grates, the latter difficulty being a problem particularly where clinkering coal is burned.

It is an object of this invention to overcome these inadequacies of prior furnace constructions and to provide a strong, adequately powerful, air tight mechanism, not only capable of reducing air leakage to an unobjectionable minimum but also of providing adequate mechanical advantage, capable of breaking loose severely encrusted and clinkered grate surfaces. It is also an object to provide a furnace construction of improved design, of neat appearance, rugged construction and one that may be built and maintained at reasonable cost.

Other and further objects of the invention are those inherent in the apparatus herein illustrated, described and claimed.

The invention is illustrated in the drawings in which

Figure 1 is a fragmentary side elevational view, partly in section, of the apparatus of the invention showing the grates in level grate position;

Figure 2 is a view corresponding to that shown in Figure 1 except that the grates are shown in the dumping position;

Figure 3 is a fragmentary cross sectional view taken along the line 3—3 of Figure 1. In Figure 3 the section line 4—4 is the line on which the sectional views shown in Figures 1 and 2 are taken;

Figure 4 is a fragmentary sectional view taken along the line 4—4 of Figure 2; and

Figure 5 is a fragmentary sectional view taken along the line 5—5 of Figure 1.

Throughout the drawings corresponding numerals indicate identical parts.

Referring to the drawings, the furnace struc-

ture includes foundation generally designated 10 having downwardly sloping ash pit floor 11. The foundation includes an air inlet which enters through one wall of the ash pit or plenum chamber, here illustrated by the duct opening 12 in the back wall of the furnace illustrated by the refractory lining 13. The refractory lining is provided with an air duct 14 so as to introduce from the air duct 12 a small amount of air above the fire via arrow 15.

The under-grate air plenum space may operate under positive or negative pressure depending upon whether natural, induced or forced draft is used but in any event the volume of air supplied to the under side of the grate must be controlled carefully, thus requiring that leakage be minimized, so that suitable damper control will be effective. The grate surfaces are supported upon side rails and cross frame members. In this instance the grate is a "double grate" and having a middle pier of the foundation at 16 and side walls of the foundation at 17 and 18. Upon the side walls 17 and 18 are grate side frame members 20 and 21 and upon the middle pier 16 there are placed back-to-back a similar pair of side frame members 22 and 23.

The side frame members 20 and 21 are provided with cap pieces 26 and 27 which are shaped so as to provide the outwardly sloping surfaces 30 at 28 and 29 so as to serve on the sides to retain the solid fuel bed burned on the grate. The surfaces 28 and 29 are provided with apertures 30 and 31, respectively, through which combustion air is introduced. The grate side frame members 22 and 23 supported upon the middle pier are likewise provided with caps 34 and 35, respectively, of somewhat different design, shaped so as to present a level grate surface equal to that afforded by the grate bars hereinafter described. It is to be understood, of course, that the cap grates 34 and 35 form an immovable tier along the center of the grate area.

The side frame members 20—22 and 21—23 are held together at their ends by cross frame members. Thus, referring to Figures 1 and 2 there is illustrated a front cross frame member 36 which is suitably supported on the foundation and is attached to the side frame members, in this instance members 21 and 23. The front cross frame member is provided with a grate area indicated under the bracket 37 which has an irregular upper surface and is provided with air slots 38. An overhanging front flange 39 on the cross frame member is spaced from the main body of the cross frame member so as to provide a re-

cess into which one flange 40 of the channel 31 is adapted to fit. The channel 31 serves as part of the furnace structure and to it there is bolted a door structure 42 by means of bolts 43. The channel is filled by a refractory filling 44.

At the rear of the furnace the grate side frame members, in this instance members 21 and 23, are attached together by a cross frame member illustrated at 48 having suitable apertures 49 and 50 therein for the passage of under grate air through the member.

Upon the cross frame member 48 there is positioned a cap member generally designated 52 which is provided with air inlet openings 53 for supplying combustion air to the solid fuel which beds against the cap. It will be noted that an air space is provided at 54 between the rear wall formed by the cross frame member 48 and a portion of the cap 52 and the machinery of the rear of the furnace illustrated at 13. It is to be understood that similar front and back cross frame members are provided for as many of the pairs of the side frame members as are included in the grate area. Thus, another pair of front and back cross frame members are provided for the side frame members 20 and 22 and in the event the grate area is three or more tiers wide additional units are installed.

The side frame members 20 and 22 (also 21 and 23) are provided with U-shaped bearing notches illustrated at 56 and 57 in Figures 1 and 2, the bearing notches on opposite side frame members being so positioned as to be directly on a line transversely across the grate area. In larger furnaces, longer side frame members are fitted to receive a larger number of carrier bars. The bearing notches have a conical bottom surface as illustrated at 58, 59, 60 and 61 in Figure 3, and into the bearing notches there are received the stub end shafts of the carrier bars generally designated 65.

Referring to Figures 1-3 the carrier bars have an intermediate portion indicated by the bracket 66 having a cross section similar to that of a railroad rail in that it has an approximately rectangular head portion 67, a web 68 and a bottom flange 69. On the ends of this intermediate section there are provided the stub shafts 70 and 71 which have a cylindrical under surface generated about an axis at the level of point 73-73. The portion of the stub shaft which is level with the top of the head portion 67 of the intermediate section is flattened off, inasmuch as it does not form a portion of the bearing surface in normal operation. The stub end shafts 70 and 71 contact the somewhat conical surfaces 58 and 59 of the bearing notches in what approaches a line contact and therefore air freely moves around the ends of the shafts and prevents overheating. It will be noted that in Figure 3 air passes from the under grate surface out around the stub shaft 71 and thence upwardly through the cap 26 or 27, as the occasion may be, and through orifices 30 and 31. The flow of air thus around the ends of the stub shafts tends to keep them cool during operation and prevents burning off. The intermediate section of the carrier bar is provided with a downwardly extending carrier bar lever 75 which is adequately side braced by gussets 76. It will be understood that the lever 75 and gussets 76 are cast integral with the intermediate section 66 of the carrier bar and that the stub shafts 70 and 71 are likewise integral. The bottom end of each of the carrier bar levers 75 is apertured at 78 to receive a tie bar 79 which is held in place by pivot

5 pins 80, the length of the carrier bar 79 and the position of the pivot connections to it being such that all of the carrier bars are held in the same relative angular position. At the forward end of the tie bar there is a downwardly protruding portion 82 which is apertured to receive a pivot pin 83 upon which there is connected the shaker link 84 extending to the lever member generally designated 90.

On the intermediate portion 66 of each carrier bar there are placed a plurality of grate bars generally designated 86 of identical construction. The grate bars are preferably of a shape and configuration as shown in my copending application Ser. No. 548,399, entitled "Shaker grate construction," filed concurrently herewith. The grate bars preferably have a top design such as shown and claimed in my copending application Ser. No. 548,398, entitled "Grate," filed concurrently herewith. Since the grate bar design per se does not form a part of the present invention, they will not be further described but reference is made to the aforesaid applications which are incorporated herein by reference.

Upon the front wall of the ash pit there is mounted a panel 88 which is held in place by a plurality of bolts 89. The panel 88 is provided with spaced parallel walls 91 and 92 which lie in planes perpendicular to the axis of rotation of the carrier bars 65. The walls 92 present an open space along the line 93 and extend through the plane of the ash pit front wall 88 and extend through the plane of the front panel rearwardly to the ash pit and terminal at line 94. The space between the walls 91 and 92 is open to the ash pit space except that the walls are fastened together at the top, as illustrated at 95 and also fastened together across the bottom by a cylindrical web 93 which is generated about the axis of pivot 96 as a center. The walls 91 and 92 are apertured to receive a pivot pin 96 which serves as a pivotal axis for the lever member generally designated 90.

The lever member 90 is of sufficient thickness so as neatly to fit into the space between the opposed surfaces of walls 91 and 92 and although it is free to move arcuately therein about the pivot pin 96, the fit is sufficiently close to preclude any detrimental outflow of the under fire combustion air around the lever 90. By the same token the lower surface 99 of the lever 90 is curved about the axis of pin 96 as a center and is of a dimension such that it neatly fits the inner surface of the web 93, thus sealing off the air flow at this point. The upper portion of the lever 90 illustrated at 101 is provided with a curved surface likewise generated about the axis of pivot pin 96 so as to fit the correspondingly curved portion 102 of the frame 95, thus serving to seal off the flow of air at this point. Thus, the lever 90 seals off the air flow between the walls 91 and 92 and the arcuate surfaces 98 and 102, regardless of the position of the lever 90.

The lever 90 is provided with a hollowed out portion 103 into which the link 84 extends and is attached to the lever 90 by means of the pivot pin 105. The length of link 84 is such that the grates 86 are in the level position (and the carrier bar operating levers 75 are in the vertical position), the lever 90 is in the position shown in Figure 1, viz., extended forwardly to its forward limit of motion, as is determined by the abutment of the shoulder 106 of the lever 90 against a corresponding surface of the frame member 98. The lever 90 is provided with a socket 108 for re-

ceiving a shaker handle 109 which may be hand or power operated, as desired. The shaker handle is oscillated back and forth in the direction of double arrow 110. The motion is communicated through pin 105 to link 84, pin 83 and thence to the tie bar 79 and through the two edges of the carrier bar levers 75 that are connected to the tie bar. It is to be understood that while only two carrier bars 65 are illustrated, more or less may be used, as desired. When the lever 109 is moved to its lowermost position, shown in Figure 2 the tie bar 79 is moved to the position in which it is engaged by the downwardly rotated forward end 111 of certain of the grate bars 86, this being the limit of motion.

Due to the fact that in the level grate position the link 84 maintains the lever 90 to its extreme forward position of rotation, shown in Figure 1, the link 84 is thereby brought nearer the axis of pin 96 than at any other place in the motion of the grate shaking mechanism. Thus, the dimension D, which is the length of the normal line from the center of pin 96 to the center line of link 84, is a minimum when the grate mechanism is in the position shown in Figure 1, and is a maximum in the position shown in Figure 2. Accordingly, the force multiplication of the leverage consisting of shaker handle 109, lever 90 and link 84 is greatest when the grate is in the level position, or just leaving the level position, and accordingly a greater force is available in such positions for breaking loose clinkers or ash that may be caked on the grate surfaces. This is a distinct advantage inasmuch as the greatest force is needed when initiating the grate shaking operation. Once the encrusted ash and clinkers are broken loose the shaking operation is much easier than at the start of the shaking operation. Throughout the shaking operation, with the shaker mechanism and grates in any position, the out flow of under grate combustion air is prevented by the continuous close clearances that are maintained between the lever 90 and the appropriately shaped enclosing walls of the frame 88. In this way the escape of combustion air, which is maintained under pressure under the grate, is prevented at all times.

As many apparently widely different embodiments of this invention may be made without departing from the spirit and scope thereof, it is to be understood that I do not limit myself to the specific embodiments herein except as defined by the appended claims.

What I claim is:

1. An improved furnace construction comprising a shaker-type grate, an enclosed ashpit under said grate and means for supplying combustion air thereto, mechanical air lock, means in the ashpit enclosing wall for communicating mechanical motion to the grate without allowing detrimental air flow from the ashpit space, including a pair of spaced parallel walls extending through said ashpit wall, said walls being connected by a cylindrical segmental wall, a pivot at the center of said segmental wall portion and a movable sealing member positioned in the space between the parallel walls and mounted to swing about said pivot, said member being shaped to fit in air-retaining relation to the parallel walls and segmental wall, mechanical means connecting said movable sealing member and shaker grate so as to move the grate when the movable sealing member is actuated and means connected to the portion of the movable sealing member ex-

posed to the outside of said ash pit wall for moving said sealing member.

2. An improved furnace construction comprising a shaker-type grate, an enclosed ashpit under the grate, means for supplying combustion air to the enclosed ashpit, a mechanical air lock means in the ashpit enclosure wall for communicating mechanical motion to the grate for shaking it without allowing air-flow from the ashpit, including a pivot on the ashpit wall, said wall having an opening adjacent to the pivot, a member pivotally mounted on said pivot, said member being shaped so as to cover the opening and to maintain contact with the ashpit wall when oscillated back and forth on said pivot, means within the ashpit connecting the member and the shaker-grate for shaking the grate when the member is oscillated back and forth, and means connected to said member outside the ashpit wall for oscillating said member.

3. An improved furnace construction comprising a shaker-type grate, an enclosed ashpit under the grate, means for supplying combustion air to the enclosed ashpit, a mechanical airlock means in the ashpit wall for communicating mechanical motion to the grate for shaking it comprising a member pivoted closely adjacent the ashpit wall and swingable on said pivot through the plane of the wall through an opening in said wall, said member and wall being fitted one to the other so as to seal the air against passage through said opening, and mechanical connection means connecting said member and the grate for shaking movement of said grate when the member is oscillated on its pivot, and means connected to the portion of said member exposed to the exterior of the ashpit wall for moving said member to and fro.

4. An improved furnace construction comprising a shaker-type grate, an enclosed ashpit under the grate, means for supplying combustion air to the enclosed ashpit, a mechanical air lock means in the ashpit wall for communicating mechanical motion to the grate for shaking it, said ashpit being provided with a pivot the axis of which is parallel to the wall of the ashpit, an opening through the ashpit wall and panels perpendicular to the ashpit wall and to the axis of said pivot, a curved web connecting said panels, said curved web being generated with the pivot as a center, an oscillating member mounted for swinging movement upon said pivot, said member being shaped to fill the space between said panels and between the ashpit wall and curved web so as to seal the ashpit against outflow of air, mechanical means connecting the member and said shaker-type grate and means connected to that portion of the member exposed to the outside of the ashpit for swinging the member back and forth.

5. An improved furnace construction comprising a shaker-type grate, an enclosed pit under the grate, means for supplying air thereto, said pit having a wall with a rectangular opening therethrough, enclosure walls extending parallel to each other and perpendicular to the pit wall on two sides of said opening, a pivot mounted parallel to the plane of the wall along a third side of the opening, a curved web connecting said enclosure walls, said web being generated about the pivot as a center, a swinging member mounted on said pivot, said member being shaped so as to fit in substantial air-sealing relationship between the enclosure walls, the web and pit wall adjacent the pivot, mechanical means connect-

ing said swinging member and shaker grate and means connected to the portion of said swinging member exposed to the exterior of the pit for swinging said member.

6. The apparatus of claim 5 further characterized in that said swing member has means to receive a shaker lever.

7. An improved furnace construction comprising grate carrier bar pivotally mounted for grate shaking oscillatory partial rotation around said pivots, an enclosed pit under said grate and means for supplying air thereto, said pit having a vertical side wall, a pivot mounted horizontally close to said side wall and generally parallel to the pivotal axis of said grate carrier bars, a segment pivotally mounted thereto swinging movement in a plane extending through the pit side wall, an opening through the pit side wall so as to permit said swinging movement, said pit side wall being fitted to said segment adjacent its pivot and at each side and at the bottom so as to seal off air flow therearound, a link connecting the segment and grate carrier bar and means connected to the segment exteriorly of the pit for swinging said segment.

8. The apparatus of claim 7 further characterized in that the link is of such a length that the swing member is swung outward of said pit when the grates are in normal position.

9. The apparatus of claim 7 further characterized in that the segment has parallel side walls and a cylindrical segmental end portion.

10. The apparatus of claim 7 further characterized in that the segment has parallel side walls and is cylindrically shaped at a small diameter adjacent its pivoted end and cylindrically shaped about a large diameter at its opposite end, the ashpit wall being extended so as to embrace the segment side walls and curved to fit said large and small cylindrical portions of the side wall to seal it against air outflow.

11. An improved furnace grate mechanism comprising a carrier bar extending across the grate area and pivotally mounted on its ends, a carrier bar lever extending at an angle to the carrier bar axis, an intermediate lever pivotally mounted on the furnace pit for swinging movement of the carrier bar lever back and forth in a direction transverse to the carrier bar, a link connecting the carrier lever and the intermediate lever, said link being of sufficient length so as to hold the intermediate lever away from said carrier lever whereby the perpendicular distance between the link and intermediate lever pivotal axis is less than the distance between the intermediate lever pivotal axis and the point of con-

nection of the link to said intermediate lever, and a shaker handle fixedly connected to the intermediate lever.

12. An improved furnace grate construction comprising a carrier bar having pivot ends extending on the level across the grate area, pivotal mountings for the carrier bar, a plurality of grate bars mounted on the carrier bar, said carrier bar having a carrier bar lever extending downward therefrom when the grate bars are in the level position, an intermediate lever pivotally mounted in spaced relationship transversely with respect to the carrier bar, said intermediate lever being pivotally mounted upon an axis extending generally parallel to the pivotal axis of said carrier bar, a link connecting said carrier bar lever and said intermediate lever, said link being of sufficient length so as to cause the intermediate lever to be rotated away from the carrier bar when the latter is in normal position with the grate bar level and the carrier bar lever extending downward and so as to bring the link closer to the intermediate lever pivot than the distance between said pivot and the point of connection of the link to the intermediate lever, and shaker means connected to the intermediate lever.

13. The apparatus of claim 12 further characterized in that there are provided at least one additional parallel carrier bar identical with said first-mentioned carrier bar, each said bar being pivotally mounted and having a downwardly extending carrier bar lever, and a tie bar is pivotally connected to each carrier bar lever so as to operate them in unison.

14. The apparatus of claim 12 further characterized in that there are provided at least one additional parallel carrier bar identical with said first-mentioned carrier bar, each said bar being pivotally mounted and having a downwardly extending carrier bar lever and a tie bar is pivotally connected to each carrier bar lever so as to operate them in unison, and further characterized in that the link is pivotally connected to a downwardly extending protuberance on the tie bar.

15. The apparatus of claim 12 further characterized in that the carrier bar, grate bars and link are enclosed in an ashpit into which combustion air under pressure is forced, the intermediate lever being mounted on the ashpit wall for swinging movement through the plane of said wall, said intermediate lever and wall being formed so as to air seal the lever with reference to the wall to prevent outflow of combustion air therearound.

CHARLES V. CARROLL.
